UNITED STATES PATENT OFFICE.

WILLIAM H. NEWBROUGH, OF LANSING, MICHIGAN, ASSIGNOR TO THE "NEW WAY" MOTOR COMPANY, OF LANSING, MICHIGAN.

CARBURETER FOR EXPLOSION-ENGINES.

No. 878,824.

Specification of Letters Patent.

Patented Feb. 11, 1908.

Application filed September 12, 1907. Serial No. 392,419.

To all whom it may concern:

Be it known that I, WILLIAM H. NEWBROUGH, a citizen of the United States, residing at Lansing, Michigan, have invented 5 certain new and useful Improvements in Carbureters for Explosion-Engines, of which the following is a specification.

This invention relates to improvements in carbureters.

10 The main objects of this invention are to provide an improved carbureter for explosion engines which is very simple in construction and at the same time very effective, and one which may be accurately adjusted to secure the desired explosive mixture and, when adjusted, requires no further attention than the manipulation of the air inlet valve.

Further objects, and objects relating to 20 details of construction, will definitely appear in the detailed description to follow.

I accomplish the objects of my invention by the devices and means described in the following specification.

25 The invention is clearly defined and pointed out in the claims.

A structure embodying the features of my invention is clearly illustrated in the accompanying drawing forming a part of this specification, in which:

Figure 1 is a detail elevation, partially in vertical section, of a structure embodying the features of my invention; Fig. 2 is a detail vertical section taken on a line corresponding to line 2—2 of Fig. 1; and Fig. 3 is a vertical section taken on a line corresponding to line 3—3 of Fig. 2, showing the details of the air valve.

Referring to the drawing: the carbureter 40 chamber is preferably in the form of a cylinder, being adapted at its upper end to be connected to an engine cylinder by means of a suitable pipe as 2. At the lower end of the carbureter chamber is a suitable air inlet 3.

The liquid fuel delivery pipe 4 is arranged through the wall of the carbureter chamber in a horizontal position. This pipe is provided with a delivery opening 5, the delivery 50 opening being directed upwardly and being centrally located within the carbureter chamber. The fuel delivery pipe is preferably provided with a reducing-plug 6 at its outer end, the plug being of such size as to 55 permit the delivery of the desired quantity

of the liquid fuel. This plug is made of brass both for the reason that such a small drill is used that it needs some soft material to drill, and, further, it needs a material that will not be corroded or eaten by the gasoline, 60 changing the size of the hole.

A fuel supply pipe 7 is arranged in a vertical position without the carbureter chamber and is connected to the delivery pipe 4 by means of a suitable valve casing as 8, a ball check valve 9 being provided to prevent the return of the liquid to the supply pipe. The fuel is preferably maintained at the proper level in the supply pipe by means of a storage or feed reservoir or pump, or the like. It is not an essential that the liquid fuel be maintained at a certain fixed level, as it may be below the carbureter from one to three feet and the carbureter will still operate successfully. The check valve and suction keep the gasoline up in the pipe when once it is started. Of course, the pump is used to keep the gasoline supplied to the carbureter; and to save piping, etc., gasoline is kept fairly close to the check 80 valve.

The valve casing 8 is preferably provided with a cap 10 as illustrated. The carbureter chamber is preferably provided with an enlargement 11 opposite the fuel delivery pipe, 85 so that the passage of air through the carbureter chamber is not restricted at this point.

At the lower end of the carbureter chamber is a butterfly valve 12, adapted to control the air supply. The stem 13 of this valve is arranged through the wall of the carbureter and on its outer end is provided with a hand-piece 14.

Pivotaly mounted on the valve stem 13 is 95 a stop 16. This stop is adjustably secured to the hand piece 14 by a set-screw 17 arranged through the curved slot 15 formed therein. This stop is adapted to coact with the fixed stop 18 projecting from the wall of the carbureter chamber, in limiting the movement of the air inlet valve.

The operation of the device is as follows: In starting the engine, the valve 12 is closed so that on the suction stroke of the engine a 105 quantity of the liquid fuel is drawn into the liquid pipe and thence to the carbureter chamber. The air valve is then opened and on each charging stroke a sufficient quantity of the liquid fuel is drawn up to produce the 110

desired mixture. This is controlled by the adjustment of the air valve, as it is obvious that the more the air inlet is restricted the greater the suction on the fuel. The device 5 may be nicely adjusted by loosening the screw 17 and the stop 16, thereby permitting the valve 12 to be brought to any desired position, thereby regulating the suction on the gasolene pipe; in this manner securing the 10 desired explosive mixture. After the valve is adjusted, the stop 16 is secured in place thereon by means of the set screw, so that in operation it is only necessary to open the valve as far as the stops will permit in order 15 to secure the desired explosive mixture.

My improved carbureter is very simple and economical in structure and has practically no parts to get out of adjustment. It is intended that in practice the restricting plug 6 20 shall be inserted at the factory and the passage therein be made of proper size to secure the desired results; thereby reducing the adjustable parts to a minimum, so that the device may be operated by an inexperienced 25 workman.

By means of the adjustment for the air valve, the carbureter may be adjusted to different quantities of fuel and the varying working conditions.

30 Having thus described my invention, what I claim as new and desire to secure by Letters Patent is:

1. In a carbureter, the combination of a carbureter chamber having an air inlet at its 35 lower end and adapted to be connected at its upper end to an explosion engine cylinder; a fuel delivery pipe, provided with an upwardly directed delivery opening, arranged in a horizontal position, through the wall of 40 said carbureter chamber, such delivery pipe having a reducing-plug at its outer end; a fuel supply pipe arranged in a vertical position; a valve casing connecting said fuel supply and delivery pipes; a ball check valve 45 arranged in said valve casing; a butterfly valve arranged in said carbureter chamber below said fuel delivery pipe; a stem for said butterfly valve, arranged through the wall of said carbureter chamber; a hand-piece for 50 said stem, having a curved slot therein; a stop pivotally mounted on said valve stem, a set screw carried by said stop, arranged through said slot in said hand-piece, whereby said stop may be secured in its adjusted position thereon; and a stop on said carbureter chamber, arranged to co-act with said adjustable stop of said hand-piece, all co-acting for the purpose specified.

2. In a carbureter, the combination of a carbureter chamber having an air inlet at its 60 lower end and adapted to be connected at its upper end to an explosion engine cylinder; a fuel delivery pipe, provided with an upwardly directed delivery opening, arranged 65 in a horizontal position through the wall of

said carbureter chamber; a fuel supply pipe arranged in a vertical position; a valve casing connecting said fuel supply and delivery pipes; a ball check valve arranged in said valve casing; a butterfly valve arranged in said carbureter chamber below said fuel delivery pipe; a stem for said butterfly valve, arranged through the wall of said carbureter chamber; a hand-piece for said stem, having a curved slot therein; a stop pivotally mounted on said valve stem, a set screw carried by said stop, arranged through said slot in said hand-piece, whereby said stop may be secured in its adjusted position thereon; and a stop on said carbureter chamber, arranged to co-act with said adjustable stop of said hand-piece, all co-acting substantially as described and for the purpose specified.

3. In a carbureter, the combination of a carbureter chamber having an air inlet at its 85 lower end and adapted to be connected at its upper end to an explosion engine cylinder; a fuel delivery pipe, provided with an upwardly directed delivery opening, arranged through the wall of said carbureter chamber, 90 such delivery pipe having a reducing-plug at its outer end; a butterfly valve arranged in said carbureter chamber below said fuel delivery pipe; a stem for said butterfly valve, arranged through the wall of said carbureter chamber; a hand-piece for said stem, having a curved slot therein; a stop pivotally mounted on said valve stem, a set screw carried by said stop, arranged through said slot in said hand-piece, whereby said stop may be secured in its adjusted position thereon; and a stop on said carbureter chamber, arranged to co-act with said adjustable stop of said hand-piece, all co-acting substantially as described and for the purpose 95 specified.

4. In a carbureter, the combination of a carbureter chamber having an air inlet at its lower end and adapted to be connected at its upper end to an explosion engine cylinder; a fuel delivery pipe, provided with an upwardly directed delivery opening, arranged through the wall of said carbureter chamber; a butterfly valve arranged in said carbureter chamber below said fuel delivery pipe; a stem for said butterfly valve, arranged through the wall of said carbureter chamber; a hand-piece for said stem, having a curved slot therein; a stop pivotally mounted on said valve stem, a set screw carried by said stop, arranged through said slot in said hand-piece, whereby said stop may be secured in its adjusted position thereon; and a stop on said carbureter chamber, arranged to co-act with said adjustable stop of said hand-piece, 110 all co-acting for the purpose specified.

5. In a carbureter, the combination of a carbureter chamber having an air inlet at its lower end and adapted to be connected at its upper end to an explosion engine cylinder; 115

- a fuel delivery pipe, provided with an upwardly directed delivery opening, arranged in a horizontal position through the wall of said carbureter chamber, such delivery pipe having a reducing-plug at its outer end; a fuel supply pipe arranged in a vertical position; a valve casing connecting said fuel supply and delivery pipes; a ball check valve arranged in said valve casing; a butterfly valve arranged in said carbureter chamber below said fuel delivery pipe; and an adjustable stop for said valve for the purpose specified.
6. In a carbureter, the combination of a carbureter chamber having an air inlet at its lower end and adapted to be connected at its upper end to an explosion engine cylinder; a fuel delivery pipe, provided with an up-
- wardly directed delivery opening, arranged in a horizontal position, through the wall of 20 said carbureter chamber; a fuel supply pipe arranged in a vertical position; a valve casing connecting said fuel supply and delivery pipes; a ball check valve arranged in said valve casing; a butterfly valve arranged in 25 said carbureter chamber below said fuel delivery pipe; and an adjustable stop for said valve for the purpose specified.
- In witness whereof, I have hereunto set my hand and seal in the presence of two witnesses.
